UNITED STATES PATENT OFFICE.

CHARLES H. GEERY, OF COLUMBIA, MISSOURI.

WHIFFLETREE-HOOK.

No. 820,564.

Specification of Letters Patent.

Patented May 15, 1906.

Application filed July 20, 1905. Serial No. 270,555.

To all whom it may concern:

Be it known that I, CHARLES H. GEERY, a citizen of the United States, residing at Columbia, in the county of Boone and State of Missouri, have invented new and useful Whiffletree-Hooks, of which the following is a specification.

This invention relates to whiffletree-hooks, and has for its object to provide a device of 10 the class embodying new and improved features of simplicity, durability, and reliability.

A further object of the invention is to provide a whiffletree-hook adapted for use with a whiffletree over the end of which a slit of the 15 trace slides, and embodying means to embrace the trace and to prevent a lateral displacement of the hook.

With these and other objects in view the present invention consists in the combination 20 and arrangement of parts, as will be herein-after fully described, shown in the accompanying drawings, and particularly pointed out in the appended claims, it being understood that changes in the form, proportion, size, and 25 minor details may be made without departing from the spirit or sacrificing any of its advantages.

In the drawings, Figure 1 is a perspective view of the improved whiffletree-hook applied to a whiffletree and with a trace shown 30 in outline as applied. Fig. 2 is a view in side elevation of the improved whiffletree-hook with its open position shown in outline and with a trace shown thereon in transverse section.

Like characters of reference designate corresponding parts throughout both views.

The invention forming the subject-matter of this application is adapted to be used in 40 connection with a whiffletree, as 1, over the tapered end 2 of which slides the slit 3 of the trace 4.

In its preferred embodiment the invention comprises a plate 5, secured to the whiffletree 45 1 in any approved manner, as by the screws 6, and having upstanding ears 7 at one end. At the end opposite the ears 7 and adjacent the trace 4 the plate 5 is provided with spaced upstanding lugs 8, which may be integral 50 with the plate or secured thereto by the angular portion 9. To the plate 5 is secured a spring 10 in any approved manner, as by the pin 10^a and with one end clamped by the angular portion 9 and its opposite end extending 55 between the ears 7. Between the ears 7

is pivoted an arm 11, as by the pin 12, and having an angle 13 arranged for engagement with the spring 10. At its end opposite the pivot 12 the arm 11 is arranged and proportioned to be engaged between the lugs 8 and 60 having a downturned hook 14, embracing and retaining the trace 4, and a shoulder 15, arranged to engage the trace on the side opposite hook 14.

It will be noted that when trace 4 is engaged between the hook 14 and the shoulder 15 the arm 11 is held in position by the tension of the spring 10 against the angle 13 and that when the arm is turned upwardly on the pivot it is held by the spring in the position 70 shown in outline in Fig. 2 and permitting the free implacement or removal of the trace.

When the trace is implaced upon the whiffletree, it contacts with the lugs 8, which determines its longitudinal position upon the 75 whiffletree; but when the arm 11 is turned downward the trace is securely held between the hook 14 and the shoulder 15, thus relieving the lugs 8 from strain in the direction 80 of their least strength.

It will further be noted that the arm 11, being disposed between the lugs 8, is held from lateral displacement thereby, the strain on the lugs in which instance is in the direction 85 of their greater resistance.

Having thus described the invention, what is claimed is—

1. A whiffletree-hook embodying a plate secured to the whiffletree and having spaced upstanding lugs and a hook member pivoted 90 upon the plate and arranged to hook over and retain a trace and held from displacement by the lugs.

2. A whiffletree-hook embodying a plate secured to the whiffletree and having spaced 95 upstanding lugs at one end, a hook member pivoted to the plate at the end opposite the lugs and arranged to hook over a trace and be retained between the lugs.

3. A whiffletree-hook embodying a plate 100 secured to the whiffletree and having spaced upstanding lugs at one end, a trace provided with an opening disposed upon the whiffletree adjacent the lugs, an arm pivoted to the plate opposite the lugs and having a hook at 105 the end opposite proportioned to hook over the trace and to be retained between and from lateral displacement by the lugs.

4. A whiffletree-hook comprising a plate having upstanding spaced lugs at one end and 110

upstanding spaced ears adjacent the opposite end, an arm pivoted between the ears and provided with a shoulder proportioned and disposed for engagement between the lugs, a
5 hook carried by the arm and spaced from the lugs and shoulder and a resilient member arranged to hold the arm in operative position.

In testimony that I claim the foregoing as my own I have hereto affixed my signature in the presence of two witnesses.

CHARLES H. GEERY.
